US00D822707S

(12) **United States Design Patent** (10) Patent No.: **US D822,707 S**
 Sukumaran et al. (45) Date of Patent: ** Jul. 10, 2018

(54) **DISPLAY SCREEN WITH GRAPHICAL USER INTERFACE FOR DISPLAYING TEST DETAILS OF AN ENGINE CONTROL TEST**

(71) Applicant: **General Electric Company**, Schenectady, NY (US)

(72) Inventors: **Suseel Sukumaran**, Bangalore (IN); **Atul George Tharakaran**, Bangalore (IN)

(73) Assignee: **General Electric Company**, Schenectady, NY (US)

(**) Term: **15 Years**

(21) Appl. No.: **29/617,506**

(22) Filed: **Sep. 14, 2017**

Related U.S. Application Data

(62) Division of application No. 29/554,797, filed on Feb. 16, 2016, now Pat. No. Des. 800,739.

(57) **CLAIM**

The ornamental design for a display screen with graphical user interface for displaying test details of an engine control test, as shown and described.

DESCRIPTION

The FIGURE is a front view of a display screen with graphical user interface for displaying test details of an engine control test showing our new design.

The broken lines illustrate the display screen and portions of the graphical user interface that form no part of the claimed design.

1 Claim, 1 Drawing Sheet
